UNITED STATES PATENT OFFICE.

WILLIAM GEORGE ZEIGLER, OF CHICAGO, ILLINOIS.

INTERNAL-COMBUSTION ENGINE.

1,263,989.

Specification of Letters Patent. Patented Apr. 23, 1918.

Application filed October 20, 1917. Serial No. 197,650.

To all whom it may concern:

Be it known that I, WILLIAM G. ZEIGLER, a citizen of the United States, residing at Chicago, in the county of Cook and State of Illinois, have invented new and useful Improvements in Internal-Combustion Engines, of which the following is a specification.

This invention relates to internal combustion engines, the object in view being to produce an exceptionally high power, reliable and light weight motor particularly adapting the same for aviation or aeronautical use.

A further object of the invention is to produce an engine of few parts, involving simplicity of construction and operation, doing away with the ordinary puppet valves, springs, tappets, cam shafts and all other incidental incumbrances and substituting therefor in connection with each cylinder a simple and reliable rotary valve having a novel relation to the cylinder and piston and continuously and positively operated by means connecting the same with the crank shaft.

With the above and other objects in view, the invention consists in the novel construction, combination and arrangement of parts, herein described, illustrated and claimed.

In the accompanying drawings:—

Fig. 1 is a side elevation partly in section of the improved engine looking toward the intake and exhaust side.

Fig. 2 is a vertical cross section on the line 35 2—2 of Fig. 1.

Fig. 3 is a horizontal section through the engine showing the way of gearing the valves together and rotating the same.

Fig. 4 is a fragmentary plan view of the 40 engine.

Fig. 5 is a top view of one of the liners.

Fig. 6 is a top view of one of the valves.

Fig. 7 is a fragmentary vertical section on an enlarged scale showing the connection between each rotary valve and the liner in which it rotates.

Fig. 8 is a side elevation of one of the valves.

In the accompanying drawings, I have shown an engine comprising four cylinders but it will become apparent as the description proceeds that the invention applies equally as well to engines having any number of cylinders. The engine comprises the usual crank shaft 1, connecting rods 2 and pistons 3. It is preferred however to form

each piston with a concaved working face 4 in order to give the most efficient formation to the combustion chamber when the mixture is under compression or in other words 60 when the piston is at the beginning of its working stroke.

The cylinders 5 are cast in a block 6 and the block 6 is cast or otherwise formed integrally with the upper half 7 of the crank 65 case, the lower half 8 of the crank case meeting the upper half on a line substantially in line with the longitudinal axis of the crank shaft 1 and the two sections of the crank case being secured together by fastening 70 means as shown. Under the construction and design of the engine which will more fully appear as the description proceeds, the upper and lower sections 7 and 8 may be cast or otherwise formed of aluminum or any 75 other light weight metal. A water jacket 9 extends around each of the cylinders and each cylinder is formed with a large opening 10 extending through the head thereof, the purpose of which will be explained. The 80 upper portion of each cylinder is made gradually contracting in diameter or is of frusto-conical formation as indicated at 11.

Inserted tightly in each cylinder is a liner 12 of cast iron or other suitable material, the 85 liner 12 being of the same general shape as the interior of the cylinder 5 and extending at its lower end below the bottom of the cylinder bore for a purpose which will appear. The liner 12 has a cylindrical upper end 90 portion 13 which extends through the cylindrical opening in the top of the cylinder 5 and said portion 13 is formed with a rabbet or shoulder 14 and also threaded at 15 to receive a clamping nut 16 which rests on the 95 top of the cylinder and serves to firmly hold the liner 12 in place. The head portion 13 of the liner is also bored and threaded to receive a spark plug 17. The head portion 13 of the liner is irregular or non-circular in 100 cross section as shown in Fig. 5, being provided with an offset or lip 20, the opening 10 in the head of the cylinder also having a corresponding offset portion 21 so that when the liner is in position, it is prevented from 105 turning within the cylinder. As shown in Fig. 5, the liner 12 is formed in the frusto-conical portion thereof with an intake port 18 and an exhaust port 19 and it will be observed that said ports are arranged close 110 to each other.

Mounted within the liner 12 of each cyl-

inder is a rotary valve 22 having the same general formation as the liner and also having formed in the frusto-conical upper end portion thereof diametrically opposite ports 23 and 24 which, during the rotation of the valve, register with the intake and exhaust ports 18 and 19 of the liner. It will be understood that each cylinder is also provided with intake and exhaust ports 25 and 26 for each cylinder, the intake ports 25 communicating with an intake manifold 27 and the exhaust ports 26 communicating with exhaust pipes 28 which may be joined in the manifold if so desired. The valves 22 extend below the lower ends of the liners 12 and have ring gears 29 fast thereon and positioned against annular flanges 30 extending outwardly from and formed integrally with said valves. The flanges 30 are peripherally threaded to receive ring couplings 31 which are threaded on the flanges 30 and which have inwardly extending flanges 32 which bear against other outwardly extending flanges 33 at the bottom of the liners 12. The construction just described provides for supporting the valves 22 in relation to the liners, the latter being supported by the cylinders. The ring gears 29 all mesh with each other as shown in Fig. 3 and motion is imparted to the two end ring gears by pinions 34 located at opposite ends of the engine and having a fixed relation to pinion shafts 35 extending downwardly therefrom and journaled in bearing extensions 36 within the crank case, each of said bearing extensions embodying a removable bearing cap or section 37 secured in place by fastening means 38. The shafts 35 carry at their lower ends bevel gears 39 which mesh with other bevel gears 40 on the crank shaft 1. Thus continuous rotary motion is imparted to all of the valves which rotate in the direction indicated by arrows in Fig. 3.

Each coupling ring 31 is formed in the inner edge thereof with a plurality of lubricating orifices 42 and the liner 12 is formed with lubricating holes 43 therethrough for conveying oil to the contacting surfaces of the liner and the rotary valve, the pistons and inner surfaces of the valves are lubricated by the splash system. By reason of the construction above described an engine of long life, high speed, great power efficiency and reliability is obtained combined with light weight adapting it for aeronautical purposes and a material reduction in the number of parts, the engine embodies an exceedingly simple valve construction which is positive in action and the timing of which is perfect and constant. The ports are of large size and capacity and form direct passages for the intake and exhaust. The motor improves with use whereas engines having valves of the puppet type de-

teriorate or lose power rapidly. By reason of the fact that the valve action is positive and does not depend on the uncertain operation of springs, the power increases with the speed of the motor far beyond the point where the power of a puppet valve motor begins to fall off. Any cooling system may be employed in connection with the improved engine and also any desired oiling system as well as any ignition system and any type of carburetor. The particular formation of the compression chamber gives a minimum surface area for the volume of gas, less head energy is lost through radiation and less cooling water is required to maintain the proper temperature. The result is a reliable, smoothly running mechanism that will operate efficiently and consistently with much less care and attention than the engines now in general use. The intake port of each cylinder may have a "lag" space or offset recess 44 and the exhaust port may have a "lead" space or offset recess 45 if desired. It is also proposed to spirally groove the outer surface of each of the rotary valves 22 so that the oil flowing in through the holes 43 will be carried upwardly to properly and thoroughly lubricate the contacting surfaces of the valves and liners. The ring gears 29 are four times as large as the pinions 34 so that a comparatively slow movement is imparted to the valves 22, each of said valves making one complete revolution to four complete revolutions of the crank shaft. On this account the intake and exhaust ports 18 and 19 are arranged close together as shown in Fig. 5 while the ports 23 and 24 of the valve are arranged one hundred and eighty degrees apart or diametrically opposite each other. The distance between the ports 18 and 19 represents the time consumed between the intake and exhaust strokes of the piston.

I claim:

1. In an internal combustion engine, the combination of a cylinder having an upwardly contracting frusto-conical head portion formed with intake and exhaust ports, and also having an opening through the head thereof, a liner of the same general formation as the interior of the cylinder fitted therein and having a head portion extending through and beyond the opening in the cylinder head, means engaging the head portion of the liner for fastening the same in fixed relation to the head of the cylinder, a rotary valve of the same general formation as the interior of the liner, and means for preventing longitudinal movement of said valve in relation to said liner, and a piston working within and in contact with said valve.

2. In an internal combustion engine, the combination of a cylinder having an up-

- wardly contracting frusto-conical head portion formed with intake and exhaust ports, and also having an opening through the head thereof of non-circular formation, a 5 liner of the same general formation as the interior of the cylinder fitted therein and having a head portion extending through and beyond the opening in the cylinder head, the last named opening correspond- 10 ing in shape with the shape of the head portion of the liner, means engaging the head portion of the liner for fastening the same in fixed relation to the head of the cylinder, a rotary valve of the same general 15 formation as the interior of the liner, and means for preventing longitudinal movement of said valve in relation to said liner, and a piston working within and in contact with said valve.
- 20 3. In an internal combustion engine, the combination of a cylinder having an upwardly contracting frusto-conical head portion formed with intake and exhaust ports, and also having an opening through the 25 head thereof, a liner of the same general formation as the interior of the cylinder fitted therein and having a head portion extending through and beyond the opening in the cylinder head, means engaging the head 30 portion of the liner for fastening the same in fixed relation to the head of the cylinder, a rotary valve of the same general formation as the interior of the liner, means for preventing longitudinal movement of said 35 valve in relation to said liner, consisting of a nut threaded upon the head portion of the liner and bearing against the cylinder head, and a piston working within and in contact with said valve.
- 40 4. In an internal combustion engine, the combination of a cylinder having a frusto-conical head portion and also formed with an opening extending through the head thereof, a liner of the corresponding formation 45 fitted in said cylinder and having a head portion extending through said opening in the cylinder head, liner retaining means engaging the cylinder head, said cylinder and the frusto-conical portion of the 50 liner being formed with aligned intake and exhaust ports, a rotary valve of the same general formation as said liner mounted in the latter and extending below the lower extremity of the liner, the liner extending 55 below the cylinder bore, and a coupling ring connecting said liner and valve to prevent longitudinal movement of the latter, and a piston working within and in contact with said valve.
- 60 5. In an internal combustion engine, the combination of a cylinder having an upwardly contracting frusto-conical head portion formed with intake and exhaust ports, and also having an opening through the 65 head thereof, a liner of the same general for-
- mation as the interior of the cylinder fitted therein and having a head portion extending through and beyond the opening in the cylinder head, means engaging the head portion of the liner for fastening the same 70 in fixed relation to the head of the cylinder, a rotary valve of the same general formation as the interior of the liner, means for preventing longitudinal movement of said valve in relation to said liner, a piston 75 working within and in contact with said valve, and an ignition element inserted through the head portion of the liner.
6. In an internal combustion engine, the combination of a cylinder having a frusto- 80 conical head portion and also formed with an opening extending through the head thereof, a liner of corresponding formation fitted in said cylinder and having a head portion extending through said opening in 85 the cylinder head, liner retaining means engaging the cylinder head, said cylinder and the frusto-conical portion of the liner being formed with aligned intake and exhaust ports, a rotary valve of the same general 90 formation as said liner mounted in the latter and extending below the cylinder bore, and a coupling ring connecting said liner and valve to prevent longitudinal movement of the latter, and a piston working within and 95 in contact with said valve, said valve having diametrically opposite ports to register with the intake and exhaust ports of the liner and cylinder, the last named ports being out of diametrical line with each other. 100
7. In an internal combustion engine, the combination of a cylinder having a frusto-conical head portion and also formed with an opening extending through the head thereof, a liner of the corresponding formation 105 fitted in said cylinder and having a head portion extending through said opening in the cylinder head, liner retaining means engaging the cylinder head, said cylinder and the frusto-conical portion of the liner being 110 formed with aligned intake and exhaust ports, a rotary valve of the same general formation as said liner mounted in the latter and extending below the lower extremity of the liner, the liner extending below the 115 cylinder bore, a coupling ring connecting said liner and valve to prevent longitudinal movement of the latter, a piston working within and in contact with said valve, said liner being formed adjacent to the bottom 120 thereof with lubricating holes extending therethrough, and the coupling ring being formed in its inner edge with lubricating orifices.
8. In an internal combustion engine, the 125 combination of a cylinder having a frusto-conical head portion and also formed with an opening extending through the head thereof, a liner of the corresponding formation fitted in said cylinder and having a head 130

portion extending through said opening in the cylinder head, liner retaining means engaging the cylinder head, said cylinder and the frusto-conical portion of the liner being formed with aligned intake and exhaust ports, a rotary valve of the same general formation as said liner mounted in the latter and extending below the lower extremity of the liner, the liner extending below the cylinder bore, a coupling ring connecting said liner and valve to prevent longitudinal movement of the latter, a piston working

within and in contact with said valve, said valve being provided with diametrically offset ports to register with the intake and exhaust ports of the liner and cylinder, the last named ports being located on the same side of the engine, and driving means between the crank shaft and said valve whereby one complete revolution of the valve is effected in four complete revolutions of the crank shaft.

In testimony whereof I affix my signature.
WILLIAM GEORGE ZEIGLER.
